FLIER CONSTRUCTION

Michael J. McHale, Scranton, Pa.

Application July 31, 1931. Serial No. 554,311

13 Claims. (Cl. 117—23)

This invention relates to improvements in fliers for spinning machines, and more particularly to improved bearing members for use with such fliers.

8. The present improvements are more particularly adapted for use with the novel fliers disclosed in my Patents 1,813,893 and 1,813,894, dated July 7, 1931.

The combinations hereinafter described comprise certain novel flier constructions including a novel spring gripping member, and improved friction-resistant bearing members incorporated in or adapted to be otherwise operatively associated with flier blocks of the types severally 10 disclosed and claimed in my applications, above referred to.

An object of this invention is to provide an improved bearing member for a flier which is readily adjusted.

20. Another object of this invention is to provide such improved bearing members comprising a plurality of separately adjustable and replaceable parts.

A further object of this invention is to provide 25 such improved bearing members for fliers in conjunction with a readily replaceable spring member.

With these and other objects in view, which may be incident to my improvements, the invention consists in the parts and combinations to be hereinafter set forth and claimed, with the understanding that the several necessary elements, comprising my invention, may be varied in construction, proportions and arrangement, 30 without departing from the spirit and scope of the appended claims.

In order to make my invention more clearly understood, I have shown in the accompanying drawings means for carrying the same into practical effect, without limiting the improvements 40 in their useful applications to the particular constructions, which for the purpose of explanation, have been made the subject of illustration.

In the drawings, like numerals refer to similar 45 parts throughout the several views, of which

Figure 1 is an enlarged vertical section through the upper part of a bobbin and spindle, showing an improved flier assembly in position.

Fig. 2 is a top plan view of an improved flier 50 bushing;

Fig. 3 is a horizontal section, taken on line 3—3 of Fig. 1, showing an improved spring gripping member;

Fig. 4 is a view similar to Fig. 1, showing a 55 modified form of flier and associated bushings;

Fig. 5 is a view similar to Fig. 4, showing a modified form of bushing and associated spring;

Fig. 6 is an exploded perspective view of the bushing and spring shown in Fig. 5, and

Fig. 7 is a vertical section similar to Fig. 4 60 showing thrust washers and spring.

Referring now to the drawings, there is shown a bobbin 1, mounted on a spindle 2, and adapted to rotate therewith. A flier block 3, comprising nested members 4 and 5, in threaded engagement with each other, is adapted to retain a flier wire 6 in operative engagement. The flier may be made of any suitable material such as brass, bronze, iron, and turned up or cast from the same, or it may be made of moldable condensation products, such as the reaction product of phenol and formaldehyde, or from other thermoplastic molding compounds, having the necessary physical properties.

A bushing 7, of hardened steel, or any other suitable wear-resisting material, is forced into the central aperture of member 4, the latter being preferably countersunk to receive the flange 8 of the bushing. A washer 9, is fitted in the member 5, in a force fit, and provides a bearing surface for the tabular flanges 10, of the split collar spring member 11, which is forced downwardly into gripping engagement with the spindle. Any suitable number of tabs may be formed on the flange of the spring 11, but it is preferred to have enough as shown in Fig. 3, to provide a substantially continuous support for the flier block during operation and, thus, prevent ellipsoidal oscillation of the block.

During operation of the block, the flanges 10, 90 serve to retain the block in position on the spindle, and due to the provision of the split 12 of the spring, the latter may be raised and lowered on the spindle, thus permitting the adjustment of the block to any desired operating height with 95 respect to the bobbin.

The bushing 7 is so constructed and arranged as to provide a snug bearing fit for the block on the spindle, thus aiding in preventing wobbling of the flier during operation. By using 100 suitable materials, such as hardened steel, the bushing is adapted to take up the wear normally resulting during use, and if the bushing and its associated washer, or either of them, exhibit undue signs of wear after extended use, they may be easily replaced by similar constructions, without involving the necessity of discarding the flier members.

By the use of the improvements above described, 110 the flier blocks are endowed with an appreciably

longer life, which increased life permits marked economies in replacement of these parts. As a result of extensive operative tests of the improvements herein described, the blocks of the present invention have an expected operative life of eighteen to twenty-four months, or longer, which is in marked contrast to that previously obtainable with such devices.

Referring now to Fig. 4, there is shown a flier block 13, comprising nested threaded members, 14, and 15, the member 15 being adapted to support the flier wire, which is locked in operative position by the member 14. The bushing 16, is shouldered to fit the cap 14, and is adapted to 15 slidably fit the base member 15.

The construction shown in Fig. 5 comprises a flier block having the cooperating members 14 and 15, as above described and being provided with a band spring 20 adapted to frictionally engage the spindle 2. The flier block assembly is retained on the spindle by the cooperation of the spring member and the improved bushing comprising an upper portion 21 and a lower portion 22 adapted to fit into the apertures 23, 24, 25 formed in the top and bottom of the block.

The upper and lower portions of the bushing comprise two similar constructions of generally cylindrical shape having shoulder portions 25, set in from the outer wall and being extended upwardly as at 26 to form a cylinder of restricted diameter. The inner walls 27 of this restricted portion and 28 of the main body are respectively adapted to bear against the spindle and the spring during movement of the flier block on the spindle. The bottom 29 of the bushing portion 21 is adapted to abut against the bottom of a similar portion 22 which is reversed with respect to the first portion 21.

The bushing portions may be made of any suitable material such as hardened steel or other wear-resistant material and are preferably fitted into the central portion of member 15 in a force fit so as to rotate with the latter. By using two such members it will be seen that a plurality of members of uniform size and construction may be prepared and replacement may be readily made without requiring a special fitting for any given part of the bushing.

It will be noted that in this construction it will not be necessary to use the special flange spring above disclosed and that the ordinary band spring 20 may be used.

The construction shown in Fig. 7 involves the use of a bipartite block having a male member 13 and a female cap member 14 provided with the usual securing means such as screw threads, the two parts being adapted to hold a flier wire 6 in operative position. The band spring 20 retains the block in operative position on the spindle, thrust washers 30 and 31 being severally provided at the bottom and top of the well or chamber 32 formed in the center of the block. The washer 30 is force fitted into the member 15 and is adapted to provide a bearing surface for the spindle 2 as well as being adapted to serve as a retaining member for the bottom of spring 20. Washer 31, in like manner, is force fitted into the cap member 14 and is, in its turn, adapted to serve as a top bearing member for the spindle 2, as well as a complementary retaining member for the spring 20.

It will now be seen that there has been provided certain improvements in flier block constructions which permit a longer operative life

of such parts, together with marked economies in both installation and replacement costs.

While I have shown and described the preferred embodiment of my invention, I wish it to be understood that I do not confine myself to the precise details of construction herein set forth, by way of illustrations, as it is apparent that many changes and variations may be made therein, by those skilled in the art, without departing from the spirit of the invention, or exceeding the scope of the appended claims.

What is claimed is:

1. An improved flier for spinning machines, comprising a pair of interlocking nested members having a central aperture adapted to receive a bobbin spindle, and bipartite means fitted into the block providing wear resistant bearing surfaces, at least one of said means comprising a shouldered bushing adapted to fit into one of said nested members and providing a bearing surface for the spindle. 90

2. An improved flier for spinning machines, comprising a pair of interlocking nested members having a central aperture adapted to receive a bobbin spindle, and bipartite means fitted into the block providing a wear resistant bearing surface for said spindle, said means comprising abutted shouldered bushings fitting into said nested members. 100

3. An improved flier for spinning machines comprising a pair of nested members having a central aperture adapted to receive a bobbin spindle, and bipartite means fitted into the block providing wear resistant bearing surfaces, at least one of said means comprising a thrust washer fitting into one of said nested members and providing a bearing surface for the spindle. 110

4. An improved flier for spinning machines comprising a pair of nested members having a central aperture adapted to receive a bobbin spindle, and bipartite means fitted into the block providing wear resistant bearing surfaces, said means comprising thrust washers fitted into said nested members. 115

5. An improved flier for spinning machines comprising a pair of nested members having a central aperture adapted to receive a bobbin spindle, and bipartite means fitted into the block providing wear resistant bearing surfaces for said spindle, one of said means comprising a shouldered bushing fitting into one of said nested members, and the other of said means comprising a thrust washer fitting into the other said nested member. 125

6. An improved flier for spinning machines, including a pair of nested members having a central aperture adapted to receive a bobbin spindle, an expansible gripping member on said spindle, said gripping member comprising a band spring, having a collar formed of a plurality of tabs integral with the spring, and bipartite means fitted into the flier providing wear resistant bearing surfaces for said spindle, said means serving as thrust bearings for said gripping member. 130

7. An improved flier for spinning machines, including a pair of nested members having a central aperture adapted to receive a bobbin spindle, an expansible gripping member on said spindle, said gripping member comprising a band spring, having a collar formed of a plurality of tabs integral with the spring at one end thereof and bipartite means fitted into the flier and rotatable therewith providing a wear resistant bearing surface for said spindle, said means serving as thrust 145

bearings for the collar of said gripping member.

8. A gripping member for spinning machine fliers comprising a band spring having a collar formed of a plurality of tabs integral with the spring at one end thereof, said tabs presenting a substantially continuous bearing surface.

9. A flier for spinning machines comprising a pair of screw-threaded nested members having a central aperture adapted to receive a bobbin spindle, a pair of complementary wear-resistant shouldered bushings fitting into the nested members and an expandable member in endwise engagement with the bushings and adapted to grip the spindle.

10. A flier for spinning machines comprising a pair of internally shouldered screw-threaded nested members having a central aperture adapted to receive a bobbin spindle, a pair of complementary wear resistant bushings fitting into the nested members, said bushings having shoulder portions abutting the internal shoulders of the nested members, and an expandable spring in endwise engagement with the bushings and adapted to grip the spindle.

11. A flier for spinning machines comprising a pair of screw threaded nested members having a central aperture adapted to receive a bobbin spindle, one of said nested members having an internal shoulder portion, a spindle bearing liner for the nested members comprising a tubular bushing having a restricted portion at one end

thereof forming an external shoulder with the body of the bushing, said shoulder abutting the internal shoulder formed on one of the nested members, a thrust washer fitting into the other nested member and an expandable spring between the tubular bushing and the thrust washer adapted to grip the spindle.

12. A flier for spinning machines comprising a pair of screw threaded externally shouldered nested members having a central aperture adapted to receive a bobbin spindle, a spindle bearing liner for the nested members comprising a tubular bushing having a shoulder portion seating in one of the nested members, a thrust washer seated on the shoulder of the other nested member and a gripping member on the spindle comprising a band spring having a collar formed integral therewith, the bearing liner and the thrust washer serving as thrust bearings for the collar of the gripping member.

13. An improved flier for spinning machines including a pair of screw threaded nested members having a central aperture adapted to receive a bobbin spindle, an expandable gripping member on said spindle comprising a band spring and bipartite bearing means force fitted into the nested members and rotatable therewith, providing wear-resistant bearing surfaces for the spindle, said means serving as thrust bearings for the spindle gripping member.
